REAR-DOOR LATCH FOR AUTOMOBILES

Filed Oct. 21, 1940

Fig. 1.

UNITED STATES PATENT OFFICE

2,261,674

REAR-DOOR LATCH FOR AUTOMOBILES

George E. Davelaar, Tacoma, Wash.

Application October 21, 1940, Serial No. 362,055

1 Claim. (Cl. 292—182).

This invention relates to devices for preventing the opening of the rear door of an automobile so long as the front door thereof is closed, and has for its objects to provide such a mechanism which is of extreme simplicity; which will not readily get out of order; which will automatically lock the rear door when the front door is closed and will release the locking latch when the front door is open; which will permit the rear door to be closed after the front door has been closed and will automatically lock it when so closed; which is applicable to doors which swing in the same or in opposite directions; and which is positive in its action at all times.

I attain these and other objects by the devices, mechanisms, and arrangements illustrated in the accompanying drawing, in which—

Fig. 1 is a section at the door post, showing my improved latch released from locking the rear door; Fig. 2 is a similar view showing the front door closed and the rear door locked; Fig. 3 is a similar view showing the front door closed and the rear door being closed; Fig. 4 is a section showing a modified form of my invention adapted for use when the two doors swing in the same direction; and Fig. 5 is a side view of a portion of an automobile body showing the location of my improved rear-door latch.

Similar numerals of reference refer to similar parts throughout the several views.

I am aware that several appliances of this general character have been devised but they all are either too expensive on account of their complexity, or are too easily put out of order, to meet the practical requirements of everyday use. It is my main purpose to produce such a latch mechanism as will be simple, cheap and "fool-proof."

Referring to the drawing, the body 1 of the automobile is provided with a front door 2, hinged at 3, and a rear door 4, hinged at 5. The two doors 2 and 4 are separated by a door-post 6 when the doors are swung towards each other as shown in Figs. 1, 2, 3, and 5. The form of my invention shown in Fig. 4 will be described later.

The front door 2 is provided with a slot having an inclined base surface 1, inset into its inner edge 8 adjacent to the post 6, and with a dent 9 which is adapted to receive the front end of the latch bolt. No other change is made in the front door.

The door-post 6 is provided with a latch bolt 10 mounted in suitable holes therein and extending out therefrom. A spring 11 is mounted on said bolt 10 and engages a stop pin 12 in 55

the bolt 10 to impel the bolt 10 towards the front door 2. The front end 13 of the bolt 10 is chamfered to enter the dent 9 in the front door 2. When the front door 2 is open (Fig. 1) the bolt 10 extends out from the post 6 and, as the front door 2 closes, the end 13 of the bolt 10 engages the inclined surface 7 of the slot, whereby it is forced back into the locking position, shown in Figs. 2 and 3.

The rear door 4 is provided with an open slot 14 in its edge 15 and extending outward from its inner edge, said slot 14 being adapted to allow the rear end 16 of the latch bolt 10 to pass, when the bolt 10 is pushed rearward by the front door 2 (Fig. 3), and when the rear door 4 is being opened or closed. A flat spring closure plate 17 is secured to the inner side of the rear door 4 at the said slot 14, said plate forming a resilient inclined inner wall for the said slot 14 and engaging the inner side wall 15 of the door 4 and, when so positioned, its edge 18 engages the inner side of the bolt 10 (Fig. 2) and thereby prevents the opening of the door 4.

However, if the front door is closed while the rear door 4 is open, the said rear door 4 may be closed because, as shown in Fig. 3, the rear end 16 of the bolt 10 engages the inclined side of the resilient closure plate 17 as the door 4 closes, thus forcing the closure plate 17 away from the wall 15 and permitting the bolt 10 to completely pass the plate 17 which, at once, returns to its normal position and locks the said door 4, as above.

To unlock the rear door 4, all that is necessary to do is to open the front door 2, thus releasing the bolt 10, which is impelled forward by the spring 11 (Fig. 1).

I prefer to locate my improved rear-door latch near the lower end of the door-post 6, as shown in Fig. 5, because in this position the protruding end 13 of the bolt 10 is shielded from catching on clothing or otherwise obstructing the front-door opening, by the front seat structure which normally extends in front of the said post 6; it may, however, be located at any desired or convenient part of the door-post 6.

Referring now to the modified form of my invention illustrated in Fig. 4, it will be observed that I have positioned the fastening much nearer to the inner wall of the car than in the above-described form. The purpose of this arrangement is to effect the movement of the locking means during the last few degrees of movement of the rear door.

The front door 19 is provided with a slot 20

which, in this case does not need to be very long, and with a dent 21. The doorpost 22 is provided with a spring actuated bolt 23 similar to the above described latch bolt 10. The front edge 24 of the rear door 25 is hinged at 26 to the doorpost 22, and is provided with a recess 27 in line with the end of the spring bolt 23. A latch bolt 28 is mounted in the said recess 27 and is provided with a head 29 therein, adapted to be engaged by the end of the bolt 23. A spring 30 engages the head 29 to impel the bolt 28 towards the front. The latch bolt 28 extends entirely across the width of the door 25 and extends through a hole in its rear edge 31. A slot 32 is made in the outer edge of the rear door-post 33, to permit the rear end 34 of the latch bolt 28 to pass as the door 25 is opened or closed. A flat spring 35 is secured in inclined position to the outer side wall of the door-post 33 and is normally adapted to lie against the front wall thereof.

A stop pin 36 in the latch bolt 28 prevents the end 34 thereof from disengagement with the rear edge 31 of the rear door 25.

Thus it will be seen that when the rear door 25 is closed it cannot be opened as long as the front door 19 is closed. But, as soon as the front door 19 is opened, the bolt 28 is impelled forward, thereby removing the pressure on the head 29 and permitting the latch bolt 28 to move forward under the action of the spring 30, thereby removing the end 34 of the bolt 28 out of engagement with the edge of the flat spring 35 and permitting the rear door 25 to be opened. If, however, the front door 19 is closed and the rear door 25 is open, the head 29 is disengaged from the bolt 28, and the end 34 is withdrawn from its protruding position by the spring 30. As the door 25 is being closed the said bolt 28 remains in such withdrawn position until the door is almost closed, when the head 29 again engages the end of the bolt 28 and is pressed rearward. The rear end 34 of the bolt 28 then

engages the flat spring 35 as the door closes, and when it is closed the spring 35 returns to its locking position against the side of the latch bolt 28.

It is to be understood that the width of the slots 7, 14, 20 and 32 may be made only wide enough to permit the bolt ends to freely pass, but that the flat springs, or closures, 17 and 35 are slightly wider than the slots so as to engage the inner surface of the walls in which the slots are made.

Having described my invention, what I claim is:

An automatic rear-door latch for automobiles having two doors, side by side, each door closing in association with a door-post, wherein the front door is provided with a depressed surface, inclined outward from its inner edge adjacent the door post, and wherein the rear door is provided with a cut-away portion of its edge adjacent the door-post; comprising a flat, resilient, closure plate in said cut-away portion and having its exposed surface inclined outward from the inner edge of said rear door and pressing against the inner surface of the end wall of said rear door adjacent said cut-away portion, said closure plate being secured to the inner surface of said rear door; and a forward-impelled latch-bolt mounted in the door-post, the front portion thereof extending into said depressed surface of the front door and adapted to be forced rearward thereby upon closing said front door, and the rear portion thereof extending, when thus forced rearward, into the cut-out portion of the rear door and engaging said closure plate to force it rearward as the rear door is being closed, and to engage the outer end of said closure plate when the rear door is closed, whereby the rear door is held in closed position until the front door is opened to release the latch-bolt from engagement with the end of said closure plate.

GEO. E. DAVELAAR.
